UNITED STATES PATENT OFFICE.

WILLIAM S. HAMM, OF HUBBARD WOODS, ILLINOIS, ASSIGNOR TO THE ADAMS & WESTLAKE COMPANY, A CORPORATION OF ILLINOIS.

LAMP.

1,079,124.

Specification of Letters Patent. Patented Nov. 18, 1913.

Application filed June 26, 1912. Serial No. 705,949.

To all whom it may concern:

Be it known that I, WILLIAM S. HAMM, a citizen of the United States, and resident of Hubbard Woods, county of Cook, and State of Illinois, have invented certain new and useful Improvements in Lamps, of which the following is a specification, and which are illustrated in the accompanying drawings, forming a part thereof.

10 The invention relates to lamps especially adapted for switch and signal service in railroad work; and its object is to provide improved means for securely holding the font within the lamp so as to prevent the illuminating agent from being moved by jars or vibration, incident to service, away from the axis of the lamp.

It consists essentially in a detent carried either by the font or its seat and yieldingly 20 engaging a vertically facing shoulder on the other of said members.

In the accompanying drawings illustrating the invention, Figure 1 is a detail vertical section of the lamp across the font, taken on the line 1—1 of Fig. 2; Fig. 2 is a plan section, on the line 2—2 of Fig. 1; and Figs. 3 and 4 are, respectively, vertical and plan detail sections of the lamp casing and font showing a modified form of construction.

30 The lamp body is represented at 10, and is shown as being provided with a pair of lenses 11, 12, in its side walls. The body is provided with a substantially flat bottom 13, upon which the font 14 rests, and with up-standing walls 15, 16, rising from the bottom 13 and at their upper ends being inclined outwardly and upwardly, as shown at 17, 18, these inclined portions extending to the side 40 walls of the body.

In the construction illustrated in Figs. 1 and 2, there is shown a pair of leaf springs 19, 20, housed within the spaces inclosed between the walls 15, 16, and the outer walls of 45 the lamp body, each spring being securely anchored at one end, as shown, by means of rivets securing it to the walls of the body, the body portion of each spring lying against one of the upstanding walls and being 50 looped or offset through a portion of its length, as shown at 21, 22, to extend through a suitable aperture within the wall and engage the font. Shoulders are provided on

the side walls of the font for engagement by the offset portions of the springs, and these 55 shoulders are preferably formed by indenting the side walls of the font, as shown at 23, 24, the ends of such indentations being engaged by the shoulders formed by offsetting the springs, as described, and the bottoms of 60 the indentations being engaged by the lower edges of the springs. Preferably one of the springs, as 19, has its free end directed outwardly or toward the door 25 of the lamp and extending as a thumb-piece 26 through 65 a suitable aperture in the wall 16. The font is readily inserted and properly located upon its seat by first pressing the spring 19 by pressure upon its thumb-piece 26, and then forcing the font inwardly until its side indentations register with and receive the offset portions of the springs.

In the construction illustrated in Figs. 3 and 4, in lieu of the leaf springs shown in Figs. 1 and 2 the detent takes the form of 75 an eccentric pivotally mounted in the casing and adapted to engage a shoulder on the font, this eccentric being normally held in its advanced position by a spring. The eccentric 27 is carried by a spindle 28 stepped 80 in the floor or bottom 13 of the lamp casing, and having a bearing at its upper end in a block 29 secured to the under face of the wall 18. A helical spring 30 is shown as attached at 31 to the side wall of the casing 85 and at 32 to the eccentric at a point opposite its swell. The swell of the eccentric projects through an aperture in the vertical wall 16 of the font seat and enters the aperture or recess in the side wall of the font, as more 90 plainly shown in Fig. 4. As the font is withdrawn the eccentric will roll on the wall of the recess in the side thereof, turning its swell back of the wall through which it projects.

95 It is obvious that various changes can be made in the form of the detent and the various details of construction without departing from the scope of the invention. The detent may be applied to either one or both 100 sides of the font, the latter making with its seat a sufficiently tight fit to prevent its displacement by jarring if held at one side only.

105 By means of the construction shown and described the font is securely held to its seat against any tendency, due to jars or vibra-

tion, to displace it, and the burner 33 is thus permanently held at the axis of the lenses 11, 12.

I claim as my invention—

5. 1. In a lamp, in combination, a body, a font seated in the body and having on its side wall an upwardly facing shoulder and a pair of vertical shoulders, and a spring attached to the body and bearing against the 10 several named shoulders on the font.
2. In a lamp, in combination, a body, a font seated in the body and having its side wall indented to form an upwardly facing shoulder and a pair of vertical shoulders, a 15 spring attached to the body and bearing against the font and having an offset portion entering the indentation in the wall thereof.
3. In a lamp, in combination, a body, a font seated in the body and having parallel

side walls with indentations therein, leaf 20 springs attached to the body and bearing laterally against the font, the springs being bowed outward to enter the indentations.

4. In a lamp, in combination, a body, a font seated within the body, springs attached 25 to one of the named elements and engaging vertical and horizontal shoulders on the other.

5. In a lamp, in combination, a body having a horizontal slide-way, a font adapted 30 to enter the way and having a lateral depression, and a spring advanced detent mounted on the body and adapted to enter the depression.

WILLIAM S. HAMM.
